UNITED STATES PATENT OFFICE.

DAVID V. HOWELL, OF MONROE, NEW YORK.

WINDOW-CLEANING CHAIR.

SPECIFICATION forming part of Letters Patent No. 268,899, dated December 12, 1882.

Application filed April 18, 1882. (No model.)

To all whom it may concern:

Be it known that I, DAVID V. HOWELL, a citizen of the United States, residing at Monroe, in the county of Orange and State of New York, have invented certain new and useful Improvements in Window-Cleaning Chairs; and I do hereby declare that the following is a full, clear, and exact description thereof, reference being had to the accompanying drawings, and to the letters of reference marked thereon, making a part of this specification.

My invention relates to a chair or light scaffold adapted for use in washing or painting windows, and for like purposes. Its object is to provide a light seat which will be adapted for use in any window, and which may be securely fastened in place by devices which are simple, positive, and easily adjusted.

In the accompanying drawings, Figure 1 is a view in perspective of my improved window-cleaning chair secured in position upon a window-sill. Fig. 2 is a central vertical section thereof. Fig. 3 is a perspective view, illustrating a modified form of the invention; Fig. 4, a central section through the same, and Fig. 5 a transverse sectional view of one of the outer bolts and the plate carried thereby.

A is the frame of the chair. This frame may consist of an iron bar or tube bent in semi-circular form, as shown in Fig. 1, or be constructed in rectangular form, as shown in Fig. 3. The frame is provided with a suitable back, B, properly secured thereto, and with a seat, C, which may be of net-work, wire-work, or perforated veneer. In width the complete chair is adapted to serve as a single seat, so that it shall be as light and portable as possible. It is secured in position for use upon the window-sill to project outwardly therefrom by means of an extension of the side bars, D D, of its seat-frame, upon whose ends are fitted sliding collars E E, connected to move in unison by a transverse bar, F. These collars and their connecting-bar have free inward play 45 toward the seat, but their outward movement is arrested by means of a ratch formed upon the outer end of each bar D, and a pawl, G, hinged to the outer end of each collar to drop into and engage the ratch. (See Fig. 2.)

From the center of the connecting-bar F depends an arm, H, rigidly secured thereto, and

which is slotted longitudinally at a right angle to the bar F. Within this slot plays a threaded-bolt, K, flattened on opposite sides to prevent its turning in the slot, and which terminates 55 at its inner end in a flat-faced head or flange, a. A thumb-nut, b, is led upon the screw-bolt next to the head, to play between it and the inner face of the arm H. Upon the outer end of the bolt is placed a small plate, c, notched 60 on its inner face to engage counterpart notches on the outer face of the arm H, and the plate is confined by means of an outer thumb-nut, d. The nuts b and d permit the bolt K to be adjusted horizontally, while the longitudinal slot 65 permits a vertical adjustment thereof. The bolt is locked, when adjusted horizontally, by the thumb nut b, and vertically by the thumb-nut d, which fixes the engagement of the notched plate c with the notched face of the 70 bar H.

The seat is supported outwardly by means of toe-plates J—one on each side thereof. Each toe-plate extends at a right angle from a bolt, L, which projects downward from the under 75 side of the seat. The face of the bolt below the toe-plate is flattened to bear against the outer face of the sill, and to form with the lower face of the toe-plate a right-angled notch adapted to fit upon and embrace the outer angle or edge of the sill.

The plate J may be either secured to the bolt L, in which case its upper end is threaded and being led through an aperture in the side bar of the seat is adjusted therein as to height 85 and secured by lock-nuts m n on opposite sides of the bar, (see Fig. 2,) or the toe-plate may be left free to rotate upon the screw-bolt and be secured, when adjusted as to height, by means of a set-screw, s, working against a flat face 90 formed on the bolt, (see Figs. 4 and 5,) in which case the bolt itself is secured immovably to the seat-frame. A further support is provided for the seat-bars by means of screw-bolts P P, inserted through apertures in the bars in front 95 of the seat to bear upon the inner sill. The lower ends of these bolts P terminate in wide flat-faced heads, to prevent injury to the sill by their pressure thereon, and they are secured, when adjusted, by means of thumb-nuts o o.

Instead of having two side bars, D D, project forward to carry the clamp-arm H, I con-

template extending a single central bar, D', from the rear of the seat to project out in front thereof. This central bar, D', is to be fitted upon its outer end with a collar, E, to be controlled by a ratchet, G, in like manner as the bars D D, hereinbefore described. The arm H in such a case is secured directly to the collar E, to depend therefrom, as shown in Fig. 4.

The central bar, D', or the side bars, D D, may 10 be hinged as shown at W in Fig. 4. The central bar, D, may also be braced by bending the ends of the side bars, D D, inward to close thereon, as shown in Fig. 3.

As an equivalent for the pawl and ratchet 15 G to secure the collar E when slipped forward upon the holding-bar D or D', I contemplate the use of a pin to be inserted in one of a series of holes pierced through the bar, or of other known mechanical device for catching and 20 holding the collar in place.

In the use of the chair thus simply constructed it is placed upon the window-sill and its rearadjusting-plates, J, and bolts L are brought into position to bear upon and against the outer 25 edge of the outer sill, being properly adjusted as to height either by slipping the bolt L and its plate J up or down and securing it by the nuts m n, as in Fig. 2, or by turning the plate J up or down upon the bolt and securing it by 30 the set-screw s. (See Fig. 4.) When the adjustment of the seat to the outer edge of the sill is once effected it may remain so unaltered that thereafter the seat may be at once placed in position upon that or any corresponding sill. 35 The outer end being in position, the front arm H is moved inward until the head a of the bolt K strikes the face of the wall under the sill, whereupon it is automatically held in place and fastened by means of the pawl on the collar or collars E, from which the arm depends, 40 and a ratchet on the bar D. The bolt K is moved upward in its slot until its head, bearing against the wall, strikes also the under side of the projecting edge of the sill, whereupon it is securely set and locked by means of 45 the thumb-nuts b and d. The screw-bolts P are then extended to bear upon the sill as an

intermediate support for the arms d, and are locked by their thumb-nuts. The chair is thus firmly and rigidly secured in place and supported at all needful points, so as to afford a perfectly-secure seat or platform outside the window. It may be quickly removed by simply loosening the bolt K. When removed the arm H and its locking device may, by means 55 of the hinge W, be folded over into the chair in close, compact form.

I contemplate, as an equivalent for the vertical adjustment of the bolt K in a slot in the arm H, as shown in the drawings, a vertical 60 adjustment of the arm itself in the bar F, the slot being dispensed with and the bolt K simply left free to work horizontally through a threaded aperture in the arm.

I claim as my invention—

1. The combination, in a window-cleaning chair or scaffold with a clamp or brace adapted to support and secure its outer end, of an inner clamping-arm, H, traversing upon one or more seat-bars, D, projecting forward from 70 the seat, an automatic retaining device, G, operating to prevent an outward movement of the arm, and a stay-bolt, K, led through the arm at right angles thereto and admitting of both vertical and horizontal adjustment, all 75 substantially as and for the purpose herein set forth.

2. The combination, in a window-cleaning chair or scaffold with clamping devices securing its inner end within the window-casing, of 80 an adjustable plate, J, and screw-bolt L, adapted to engage jointly, as described, both the upper and outer faces of the outer edge of the window-sill, and to support thereby the outer end of the chair, substantially in the manner 85 and for the purpose herein set forth.

In testimony whereof I have signed my name to this specification in the presence of two subscribing witnesses.

DAVID V. HOWELL.
